BICYCLE SUPPORTING HANGER OR SIMILAR ARTICLE

David L. Edwards, 210 W. Crescent,
Elmhurst, Ill. 60126

Filed July 28, 1975, Ser. No. 599,598

Term of patent 14 years

Int. Cl. D8—99

U.S. Cl. D8—235

FIG. 1 is a front elevational view of a bicycle supporting hanger or similar article showing my new design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a front elevational view of a bicycle supporting hanger or similar article showing a second embodiment of my new design;

FIG. 8 is a right side elevational view of FIG. 7;

FIG. 9 is a left side elevational view of FIG. 7;

FIG. 10 is a rear elevational view of FIG. 7;

FIG. 11 is a top plan view of FIG. 7; and

FIG. 12 is a bottom plan view of FIG. 7.

I claim:

The ornamental design for a bicycle supporting hanger or similar article, substantially as shown and described.
